United States Patent Office.

GEORGE W. MILLER, OF WOONSOCKET, RHODE ISLAND.

Letters Patent No. 93,108, dated July 27, 1869.

IMPROVED DRILL-CHUCK.

The Schedule referred to in these Letters Patent and making part of the same.

To all whom it may concern:

Be it known that I, GEORGE W. MILLER, of Woonsocket, in the county of Providence, and State of Rhode Island, have invented a new and valuable Improvement in Drill-Chucks; and I do hereby declare that the following is a full, clear, and exact description of the construction and operation of the same, reference being had to the annexed drawings, making a part of this specification, and to the letters and figures of reference marked thereon.

Figure 1, of the drawings, is a side view, with drill, of my invention.

Figure 2 is a longitudinal section of the same.

Figure 3 is a cross-section thereof.

Figure 4, a top or bottom view of chuck.

Figure 5 is a perspective view of the same.

My invention relates to chucks for holding drills; and

It consists mainly in a novel arrangement of devices intended to serve as efficient means for the purpose named.

The letter A, of the drawings, represents a cylinder, having a thread on its inside, as shown, adapted to the thread on the outer surface of the shaft B, hereinafter described.

This cylinder has a small opening at its end, opposite the thread, adapted to the size of the shank of an ordinary drill, and is bevelled down at the point a, to provide a rest for the bevelled ends of the chucks s, described hereafter.

The letter D represents a ring, cut out in the manner shown on fig. 3, to provide suitable recesses and openings for the chucks and springs, next mentioned.

The letters s represent adjustable chucks, arranged in the recesses of ring D, as shown; and the letters v represent coiled springs, arranged in circular openings in said ring. Each end of these coiled springs is extended beyond and at right angles with the openings in which

the springs are held, and is passed into a groove on the inner side of a chuck, s, in the manner shown on fig. 4. When thus arranged, these springs serve to keep said chucks in their appropriate places.

It will be observed that both ends of chucks s are bevelled. By this means, said chucks are adapted to rest against the bevelled part of cylinder A, at the point a, at one end, while the other fits in the concave foot of the shaft B, next-mentioned.

The letter B represents a shaft, having an enlarged foot, as shown, upon which a screw is cut, adapted to the thread on the inner side of cylinder A. I also cut out the foot of this shaft, at the point c, into a concave shape, adapted to receive and operate the chucks s, in the manner hereinafter mentioned.

The extreme inner points of chucks s have small grooves, marked y, by which they are adapted to clasp the shank of a very small drill, when desirable so to do.

To operate my chuck, I drop the ring D, with chucks s arranged therein, into the cylinder A, and allow it to rest against the bevelled part of said cylinder, at the point a. I then place the shank of the drill between chucks s, and insert shaft B into the cylinder, and screw it inward, thereby gradually forcing the concave c against the bevelled ends of the chucks, until the shank of the drill is clasped as firmly as I desire.

What I claim as my invention, and desire to secure by Letters Patent, is—

A chuck for holding drills, having cylinder A, ring D, chucks s, springs v, and shaft B, constructed and arranged substantially as specified.

In testimony that I claim the above, I have hereunto subscribed my name, in the presence of two witnesses.

GEORGE W. MILLER.
